US00D442598S

(12) **United States Design Patent** (10) Patent No.: **US D442,598 S**
 Wallace et al. (45) Date of Patent: ** May 22, 2001

(54) **PORTABLE MEMORY CARD FOR STORAGE OF PERSONAL INFORMATION**

(75) Inventors: **Robert F. Wallace**, Sunnyvale; **Robert C. Miller**, San Jose, both of CA (US)

(73) Assignee: **SanDisk Corporation**, Sunnyvale, CA (US)

(**) Term: **14 Years**

(21) Appl. No.: **29/109,687**

(22) Filed: **Aug. 19, 1999**

(51) LOC (7) Cl. **14-02**

(52) U.S. Cl. **D14/436**

(58) Field of Search **D14/435-38, 478-80; 361/737, 686, 736, 752; 257/678-9; 40/124.01; 283/75-6, 901; 235/487-95, 441-3, 375; 174/52.1; 439/135, 140, 76.1; D8/347**

(57) **CLAIM**

The ornamental design for a portable memory card for storage of personal information, as shown and described.

DESCRIPTION

FIG. 1 is an isometric view of a portable memory card for storage of personal information that incorporates a first embodiment of the new design, showing the card's top, front side and right side;

FIG. 2 is a top plan view of the memory card first embodiment;

FIG. 3 is an elevational view of the the right and left sides of the memory card first embodiment;

FIG. 4 is a bottom plan view of the memory card first embodiment;

FIG. 5 is a rear side elevational view of the memory card first embodiment;
FIG. 6 is a front side elevational view of the memory card first embodiment;
FIG. 7 is an isometric view of a portable memory card for storage of personal information that incorporates a second embodiment of the new design, showing the card's top, front side and right side;
FIG. 8 is a top plan view of the memory card second embodiment;
FIG. 9 is an elevational view of the right and left sides of the memory card second embodiment;
FIG. 10 is a bottom plan view of the memory card second embodiment;
FIG. 11 is a rear side elevational view of the memory card second embodiment;
FIG. 12 is a front side elevational view of the memory card second embodiment;

FIG. 13 is an isometric view of a portable memory card for storage of personal information that incorporates a third embodiment of the new design showing the card's top, front side and right side;
FIG. 14 is a top plan view of the memory card third embodiment;
FIG. 15 is an elevational view of the right and left sides of the memory card third embodiment;
FIG. 16 is a bottom plan view of the memory card third embodiment;
FIG. 17 is a rear side elevational view of the memory card third embodiment; and,
FIG. 18 is a front side view of the memory card third embodiment.
